PISTON RING

Hsia-Si Pien, Drexel Hill, Pa., assignor to Wilkening Manufacturing Company, Philadelphia, Pa., a corporation of Delaware

Application March 20, 1948, Serial No. 16,055

11 Claims. (Cl. 309—45)

1

The present invention relates to piston-rings for internal-combustion engines, Diesel engines or the like, and it relates more particularly to compression and oil-control piston-rings.

An object of the present invention is to provide new and improved compression or oil-control piston rings for internal-combustion engines, Diesel engines or the like. Another object of the present invention is to provide a trans-split compression piston ring which is relatively simple and inexpensive to manufacture and which provides more positive, controlled and uniform pressure around its circumference with a minimum of fluttering at the free ends of the ring. Still another object of the present invention is to provide a two-piece compression piston-ring which is relatively more flexible than conventional cast compression rings whereby it provides more effective oil-scraping action during the downstroke of the piston and which is long-lasting and which can be easily installed and which can be used in piston grooves without accurately dimensioning the back or inner wall of the ring relative to the piston-groove.

Other objects and advantages of the present invention are apparent in the following detailed description, appended claims and accompanying drawings.

It has been customary in the past to construct compression piston-rings as trans-split cast members (formed of steel or cast-iron or the like) a separate expander-spring being disposed radially inward of the compression ring and being constructed and arranged to apply outward tension to the ring so as to keep it in contact with the cylinder-wall (the expander-spring being usually in the form of a radially-corrugated member which bottoms against the back or inner wall of the piston-groove, at each alternate corrugation, and which contacts the inner periphery of the piston-ring at the other corrugations). It has also been suggested in the past (for example in Patent 657,548) to construct a compression piston-ring of corrugated or coiled material having inherent tension. This construction, however, has not proven universally acceptable due to the difficulties involved in producing and maintaining uniform outward pressure as well as the relatively large cost and complexity of manufacture.

According to the present invention, there has been perfected, for the first time, a piston-ring which has some of the advantages of flexible rings (as for example higher oil-scraping action) and which can be easily and inexpensively manufactured while providing a structure which is extremely long-lasting and which, at the same

2

time, provides positive and uniform pressure all the way around its periphery.

Generally speaking, the novel piston-ring of the present invention is made up of an outer ring-portion which is of relatively flexible but non-resilient sheet-metal or the like, bent and folded into a generally closed channel cross-section which has limited axial flexibility and which presents an outermost generally-cylindrical axially-extending cylinder-contacting face; and an annular expander-spring of resilient metal or the like disposed generally in a radial plane and within the channel of the outer ring-member; the said expander-spring being formed into a generally continuous S-shaped or reversely-curved radial configuration by notches formed alternately at the outer and inner peripheries thereof.

Other features of the present invention include the formation of slots on the inner periphery of the outer ring (to provide greater flexibility without loss of compression) and the chrome-plating of the outer peripheral cylinder-contacting surface (to effect increase in wearing properties).

For the purpose of illustrating the invention, there are shown in the accompanying drawings forms thereof which are at present preferred, although it is to be understood that the various instrumentalities of which the invention consists can be variously arranged and organized and that the invention is not limited to the precise arrangements and organizations of the instrumentalities as herein shown and described.

Referring to the accompanying drawings in which like reference characters indicate like characters throughout:

Figure 1 represents a perspective view of one embodiment of the present invention in assembled position; parts being broken away better to reveal the construction thereof.

Figure 2 represents a plan view of the embodiment of Figure 1.

Figure 3 represents a vertical cross-sectional view, on an enlarged scale, generally along the line 3—3 of Figure 2.

Figure 4 represents a vertical cross-sectional view generally like that of Figure 3 but showing another embodiment of the present invention.

Figure 5 represents a fragmentary plan view of still another embodiment of the present invention; parts being broken away better to reveal the construction thereof.

Figure 6 represents a vertical cross-sectional view, on an enlarged scale, generally along the line 6—6 of Figure 5.

Figure 7 represents a fragmentary plan view showing the sheet-metal blank from which the outer ring of Figures 5 and 6 is made.

Figure 8 represents a vertical cross-sectional view generally like that of Figure 6 but showing a modified form of this embodiment.

Figure 9 represents a cross-sectional view generally like that of Figure 3 but showing a modified construction wherein the ring is provided with oil-drain openings.

Figure 10 represents a fragmentary plan view generally like that of Figure 7 but showing the sheet-metal blank from which the outer ring of Figure 9 is made.

Figure 11 represents a cross-sectional view generally like that of Figure 9 but showing a further modified form of oil-control piston-ring.

In one embodiment of the present invention shown generally in Figures 1-3, I may provide a composite two-piece compression piston-ring made up of an outer trans-split ring 20 of non-resilient flexible sheet-steel or the like to be hereinafter described in detail and an expander-spring 21 of tempered spring-steel formed into a resilient trans-split annulus adapted to be installed within the outer ring 20 to provide resilient support therefor, as will be more fully described herein.

The ring 20 is integrally formed from an elongated strip of thin flat sheet-metal which is bent to provide an outer peripheral cylinder-contacting face 22 which extends generally axially and conforms to the curvature of the cylinder 23 when the composite two-piece ring is installed within the groove 24 of a piston 25, as shown particularly in Figure 3.

When viewed in vertical cross-section, as in Figure 3, the ring 20 also includes a top side 26, a curved inner wall 27 and a bottom side 28 terminating in juxtaposition to the lower free end of the outer face 22 which, in this embodiment, extends for the full axial dimension of the piston-ring.

As indicated particularly in Figure 3, the faces 22-26-27-28 provide an inner compartment or chamber 29 which extends annularly throughout the entire circumferential dimension of the outer ring 20 and which is adapted to receive the annular expander-spring 21 which is somewhat smaller, in radial dimension, than said compartment 29 so that, when the outer periphery of the expander-spring 21 contacts the inner surface of the face 22, there is a slight radial clearance between the inner periphery of the expander-spring 21 and the curved inner wall 27 of the outer ring 20.

The outer face 22 is chrome-plated as at 30 to improve the wearing properties of the ring. The protective layer 30, instead of being chromium, can obviously be of any other metal (or alloy) which can be deposited by electro-plating, spraying, dipping, or other means. Among these are cadmium, nickel, the precious metals, etc.

The ring 20 is formed as a trans-split annulus having a gap 31 which is closed when the free ends 32 are brought into abutment during installation of the ring within the piston-groove 24 and which thereafter opens slightly when the ring 20 is expanded into contact with the cylinder-wall 23 by the expander-spring 21, as indicated in Figure 2.

The expander-spring 21, which is the subject of my co-pending application Serial No. 16,054, filed simultaneously herewith, is formed from a length of tempered spring-steel having a general-

ly rectangular cross-section, as indicated particularly in Figure 3; radially-extending slots 33 and 34 being formed along the inner and outer peripheries respectively in alternating relationship.

The thickness or axial dimension of the expander-spring 21 is very slightly less than the axial dimension of the compartment 29, while its radial dimension is appreciably less than that of the compartment 29, as mentioned above, so that the expander-spring 21 can be installed within the compartment 29 by spreading apart the free ends of the outer ring 20 and by similarly spreading apart the free ends 35 of the expander-spring 21 and by inserting one of the free ends 35 within the end of the compartment 29 and thereafter pushing the expander-spring until it is fully enclosed within the outer ring 20, as indicated in Figure 2.

The tension of the expander-spring 21 will then bring the assembled unit back more or less to the original curvature.

It is desirable that the free ends 35 of the expander-spring 21 be circumferentially spaced somewhat from the free ends 32 of the outer ring 20.

With the expander-spring 21 thus contained within the compartment 29 of the outer ring 20, the unit can be quickly and easily installed by first manually spreading the outer rings sufficiently to pass over the piston, after which the unit will collapse within the piston-groove 24 and, thereafter, any conventional compression tool can be used to install the piston 25 within the cylinder 23.

As is apparent from Figure 1, the radial dimension of the outer ring 20 is less than that of the piston-groove 24 so that, when the ring is maintained in continuous resilient contact with the cylinder-wall 23, as shown in Figure 1, there is an appreciable radial clearance between the inner curved wall 27 of the ring 20 and the back wall 36 of the piston-groove 24.

From the foregoing it is apparent that, when installed on a piston and within a cylinder, the novel compression piston-ring of the present invention is maintained in resilient contact with the cylinder wall by the expander-spring 20. That is, the expander-spring 20 (which, in the installed position, is compressed with its ends in substantial abutment) provides a "free-floating" circumferentially generally uniform support for the outer ring 20 without the need for "bottoming" against the back wall 36 of the piston-groove 24.

Due to the relative flexibility of the outer face 22 and the fact that the pressure of the expander-spring is applied directly thereto, a more positive controlled and uniform pressure is possible all around the circumference of the piston-ring. Moreover, the internal supporting action of the expander-spring minimizes the fluttering of the free ends 32 ("fluttering" being an undesirable tendency in conventional solid compression rings).

The circumferential flexibility of the outer ring 20 permits the ring to conform more accurately to the cylinder-wall, especially where the cylinder-wall is slightly "out of round" due to wear.

The axial flexibility of the ring provides more efficient oil-scraping action than is possible with conventional non-flexible imperforate compression rings.

As mentioned above, the protective coating 30 increases the effective life of the piston-ring and

provides a long period of efficient operation at low cost.

In Figure 4, I have shown another embodiment of the present invention which generally resembles the embodiment of Figure 1, described above, except that the outer ring 20—a is slightly differently bent so that the bottom side 28—a extends all the way out to the outer periphery of the ring while the outer face 22—a has an axial dimension which is shorter than the face 22 by the thickness of the bottom side 28—a. In this way, the cylinder-contacting surface of the ring 28 is made up of the face 22—a and the free end of the side 28—a (the free end of the face 22—a being in juxtaposition with the upper surface of the bottom side 28—a, as indicated in Figure 4).

The protective coating 30—a, in this embodiment, extends across the outer surface of the face 22—a and also across the end of the bottom side 28—a.

The other elements of the ring of Figure 4 are identical with those described hereinabove in connection with the embodiment of Figure 1. The embodiment of Figure 4, however, provides slightly better oil-scraping action due to the slightly greater flexing permitted by the split-construction provided by the bottom side 28—a.

In Figures 5 and 6, I have shown still another embodiment of the present invention which generally resembles that of Figure 4 except that the outer ring 20—b is given somewhat greater flexibility by providing a series of slots 37 on the curved inner wall 27—b; the slots 37 being punched off-center, in the flat sheet-metal blank 38 of which the ring 20—b is formed, as indicated in Figure 7.

As shown in Figure 6, this embodiment employs the shortened outer face 22—a, the elongated bottom side 28—a and the protective coating 30—a of Figure 4.

In Figure 8, I have shown a slightly modified form of the embodiments of Figures 6 and 7.

In Figure 8, there is shown a slight modification of the embodiment of Figures 5 and 6 wherein the longer face 22 (with the protective coating 30) and the shorter side 28 of Figure 3 are employed in conjunction with the slots 37 described hereinabove. In this embodiment, it is apparent that in forming the blank from which the piston-ring is manufactured, the slots 37 are even further off-center (and are closer to the right-hand side of the blank when viewed as in Figure 7, by the thickness of the outer face 22).

The more-flexible constructions of Figures 6 and 8 are preferably used only in the second compression groove of the piston where oil-wiping action is more essential; the less-flexible constructions of Figures 1 and 4 being preferred for the first compression groove where the pressure-sealing action is more essential.

While the novel piston-ring of the present invention is intended primarily as a compression-ring (such as is usually employed in the uppermost two or three grooves of the piston), it can also be used as an oil-control piston-ring (in the lowermost groove or grooves of the piston) by simply forming a number of oil-drain openings therein, to permit the radial flow of oil from the cylinder-wall to the oil-drain passageways of the piston in conventional manner.

Thus, in Figure 9, I have shown a modification of the embodiment of Figure 8 wherein openings 39 are formed in the outer face 22—b to provide an oil-control piston-ring; the outer face 22—b serving to wipe or scrape oil from the cylinder-

wall so that it passes through the openings 39 and is then transferred radially through the inner compartment 29 (the transfer being facilitated by the capillary action of the adjacent top and bottom walls of the ring and of the expander 21) and then through the slots 37 and into the oil-drain passageways 40 which extend radially inwardly from the cylinder-groove 24—a.

As shown in Figure 10, the ring 20—b can be formed from a sheet-metal blank wherein the slots 37 and the openings 39 are punched side by side.

In Figure 11 there is shown an oil-control piston-ring which is a modified form of that of Figure 9. In this embodiment, the outer ring 20—c has its axially-extending portion 22—c slightly inwardly displaced so that an annular fold-line or rib 41 is formed at the upper edge of the ring in axially-spaced relation to the free edge 42 of the bottom wall 28—c. The rib 41 and the edge 42 thus provide a pair of annular axially-spaced cylinder-contacting lands or ribs for the purpose of more effectively wiping oil from the wall of the cylinder 23.

In the embodiment of Figure 11, the oil-drain openings take the form of notches 43 formed in the lowermost free edge of the axial wall 22—c.

The cylinder-contacting lands 41 and 42 may be chrome-plated to reduce wear, in the manner described hereinabove.

While I prefer to employ the expander 21, it is apparent that other types of non-bottoming free-floating expander-springs could be used within the compartment 29 of the ring 20 (or 20—a or 20—b or 20—c). Thus, for example, an axially-corrugated continuous annulus of resilient sheet-metal or the like, like that shown in Patent 2,293,450, could be employed within the compartment 29 of the outer ring 20 in order to provide resilient support therefor.

The present invention may be embodied in other specific forms without departing from the spirit or essential attributes thereof, and it is therefore desired that the present embodiments be considered in all respects as illustrative and not restrictive, reference being had to the appended claims rather than to the foregoing description to indicate the scope of the invention.

Having thus described my invention, I claim as new and desire to protect by Letters Patent:

1. A composite two-piece piston-ring comprising an integral trans-split ring formed from a strip of relatively non-resilient sheet-metal folded to provide an outer peripheral wall, top and bottom walls and an inner wall forming a continuous enclosed annular compartment; and a non-bottoming resilient one-piece annular expander disposed within said compartment and providing generally uniform outward tension around the circumference of said ring.

2. A composite two-piece piston-ring comprising an integral trans-split ring formed from a strip of relatively non-resilient sheet-metal folded to provide an outer peripheral wall, top and bottom walls and an inner wall forming a continuous enclosed annular compartment, said outer wall having a generally cylindrical outer face said ring having a radial dimension in cross-section substantially greater than its axial dimension; and a non-bottoming resilient one-piece annular expander disposed within said compartment and providing generally uniform outward tension around the circumference of said ring.

3. A composite two-piece piston-ring comprising an integral trans-split ring formed from a strip of non-resilient sheet-metal folded to provide an outer peripheral wall, top and bottom walls and an inner wall forming a continuous enclosed annular compartment, said outer wall extending in continuation of the top wall for generally the entire axial dimension of said ring; and a non-bottoming resilient one-piece annular expander disposed within said compartment and providing generally uniform outward tension around the circumference of said ring.

4. A composite two-piece piston-ring comprising an integral trans-split ring formed from a strip of non-resilient sheet-metal folded to provide an outer peripheral wall, top and bottom walls and an inner wall forming a continuous enclosed annular compartment, said outer wall being formed by an axially-extending continuation of the top wall and by the free edge of the bottom wall; and a non-bottoming resilient one-piece annular expander disposed within said compartment and providing generally uniform outward tension around the circumference of said ring.

5. A composite two-piece piston-ring comprising an integral trans-split ring formed from a strip of non-resilient sheet-metal folded to provide an outer peripheral wall, top and bottom walls and an inner wall forming a continuous enclosed annular compartment, said inner wall being provided with a plurality of circumferentially-distributed openings thereby to increase the flexibility of the ring; and a non-bottoming resilient one-piece annular expander disposed within said compartment and providing generally uniform outward tension around the circumference of said ring.

6. A composite two-piece piston-ring comprising an integral trans-split ring formed from a strip of non-resilient sheet-metal folded to provide an outer peripheral wall, top and bottom walls and an inner wall forming a continuous enclosed annular compartment, said outer peripheral wall providing a continuous cylinder-contacting land, said inner wall being curved and being relieved by a plurality of circumferentially-distributed slots thereby to increase the flexibility of the ring, said ring having a radial dimension in cross-section substantially greater than its axial dimension and a resilient free-floating radially-corrugated expander-spring disposed within said annular compartment and bearing against the outer wall thereof thereby to provide generally uniform outward tension around the circumference of said ring.

7. A composite two-piece piston-ring comprising an integral trans-split ring formed from a strip of non-resilient sheet-metal folded to provide an outer peripheral wall, top and bottom walls and an inner wall forming a continuous enclosed annular compartment; and a resilient annular expander disposed within said compartment and providing generally uniform outward tension around the circumference of said ring, said expander having a plurality of slots formed alternately on the inner and outer peripheries thereof, said expander having an appreciably smaller radial dimension in cross-section than the radial dimension of said compartment.

8. A composite two-piece piston-ring comprising an integral trans-split ring formed from a strip of non-resilient sheet-metal folded to provide an outer peripheral wall, top and bottom walls and an inner wall forming a continuous

enclosed annular compartment, said outer wall having a generally cylindrical outer face, said ring having a radial dimension in cross-section substantially greater than its axial dimension; and a resilient annular expander disposed within said compartment and providing generally uniform outward tension around the circumference of said ring, said expander having generally rectangular cross-section and having radial slots formed alternately on the inner and outer peripheries thereof, said expander having an appreciably smaller radial dimension in cross-section than the radial dimension of said compartment.

9. A composite two-piece oil-control piston-ring comprising an integral trans-split ring formed from a strip of non-resilient sheet-metal folded to provide an outer peripheral wall, top and bottom walls and an inner wall forming a continuous enclosed annular compartment, said outer and inner walls being provided with openings to permit radial flow of oil through said ring; and a non-bottoming resilient one-piece annular expander disposed within said compartment and providing generally uniform outward pressure around the circumference of said ring, said expander comprising a trans-split annulus disposed generally in a radial plane and having radial slots formed alternately on the inner and outer peripheries thereof, said expander having an appreciably smaller radial dimension in cross-section than the radial dimension of said compartment.

10. A composite two-piece oil-control piston-ring comprising an integral trans-split ring formed from a strip of non-resilient sheet-metal folded to provide an outer peripheral wall, top and bottom walls and an inner wall forming a continuous enclosed annular compartment, said outer wall having a recessed intermediate portion thereby providing a pair of axially-spaced circumferential cylinder-contacting ribs, the inner wall and the recessed portion of the outer wall being provided with oil-drain openings to permit flow of oil radially through said ring; and a non-bottoming resilient one-piece annular expander disposed within said compartment and providing generally uniform outward pressure around the circumference of said ring.

11. A composite two-piece oil-control piston-ring comprising an integral trans-split ring formed from a strip of non-resilient sheet-metal folded to provide an outer peripheral wall, top and bottom walls and an inner wall forming a continuous enclosed annular compartment, said outer wall having a recessed intermediate portion thereby providing a pair of axially-spaced circumferential cylinder-contacting ribs, the inner wall and the recessed portion of the outer wall being provided with oil-drain openings to permit flow of oil radially through said ring; and a non-bottoming resilient one-piece annular expander disposed within said compartment and providing generally uniform outward pressure around the circumference of said ring, said expander comprising a trans-split annulus disposed generally in a radial plane and having radial slots formed alternately on the inner and outer peripheries thereof, said expander having an appreciably smaller radial dimension in cross-section than the radial dimension of said compartment.
